CLAIM

The ornamental design for a bathroom wall shelf, as shown and described.

DESCRIPTION

FIG. 1 is a perspective view of a bathroom wall shelf showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another perspective view of the bathroom wall shelf showing alternate configuration.

Broken lines in the drawings depict portions of the bathroom wall shelf that form no part of the claimed design.

1 Claim, 7 Drawing Sheets
